UNITED STATES PATENT OFFICE.

FAY H. MARTIN, OF HYDEPARK, MASSACHUSETTS, ASSIGNOR TO TEXTILE MACHINERY COMPANY, OF BOSTON, MASSACHUSETTS, A CORPORATION OF MAINE.

FLIER.

SPECIFICATION forming part of Letters Patent No. 760,227, dated May 17, 1904.

Application filed November 12, 1903. Serial No. 180,821. (No model.)

To all whom it may concern:

Be it known that I, FAY H. MARTIN, a citizen of the United States, residing at Hyde-park, in the county of Norfolk, State of Massachusetts, have invented a certain new and useful Improvement in Fliers for Roving-Machines, &c., of which the following is a specification, reference being had therein to the accompanying drawings.

10 The invention has relation to the fliers of roving-machines and the like machines, and in particular to the pressers of such fliers. More especially it has reference to the means and manner of combining the said pressers with the presser-carrying arms of the fliers.

In a flier of the class to which the invention relates the presser instead of being pivoted in ordinary manner upon the presser-carrying arm, so that the center of the pivot 20 constitutes the axis or center of the arc which is described by the presser-shoe in its movements, is mounted upon the arm in such a manner that as the load of roving which is being wound upon the bobbin increases in diameter and presses the shoe of the presser outward from the spindle the presser in addition to swinging outward in a radial direction is caused to move bodily in the direction of its length. The result of causing this movement bodily in the direction of its length to 30 constitute a component of the movement of the presser in the operation of the flier is to cause the shoe of the presser to travel inward and outward in a substantially horizontal direction and to stand at the same height when in its outermost position as when it occupies its innermost position. Thereby any noticeable irregularity in the positioning of the ends of the successive layers of roving which 35 are wound upon the bobbin is obviated.

The especial objects of the invention are to provide in a flier of the type which has just been described a simple, practical, and inexpensive construction of means for supporting the presser upon the carrying-arm of the flier and controlling the presser in its movements and to provide a construction in which the tendency to wear is reduced to a minimum

and which at the same time will enable worn parts readily to be replaced.

I have represented in the drawings a flier embodying the invention.

In the drawings, Figure 1 is a view in elevation, showing a spindle, a bobbin, and a flier having my invention applied thereto. 55 Fig. 2 is a view thereof looking from the left-hand side in Fig. 1. Fig. 3 is a view showing in elevation the presser-carrying arm and a presser with the cap-plate removed. Fig. 4 is a view in transverse section on the plane 60 indicated by the dotted line 44 in Fig. 1 looking in the direction that is indicated by the arrows at the opposite end of the said line.

Having reference to the drawings, 1, Fig. 1, designates the spindle of a roving-frame, 65 the upper portion thereof being indicated by dotted lines in the said figure. 2 is a bobbin surrounding the said spindle. 3 is a flier which is applied to the said spindle. The boss or nose of the flier is shown at 31. The 70 balancing-arm of the flier is designated 32 and the arm to which the presser-finger is connected is shown at 33.

4 is the presser-finger; 41, its weight-arm; 42, the presser-shoe, and 43 the guide-opening of said presser-shoe, through which the roving is led on its way to the bobbin. The body of the presser-finger has two slots 44 44 formed therethrough. The said slots stand at an inclination or angle with respect to each 80 other. Blocks or bushings 55, carried by the arm 33, are received within the slots 44 44 and support the presser-finger, and by the contact of the opposite sides of the slots with the exterior portions of the said blocks or 85 bushings the presser-finger is positioned and also controlled radially in its movements. The opposite faces 45 46 of the portion of the said body in which the slots 44 44 are formed are flat and parallel with each other. One of 90 the said faces—namely, that which is marked 45—fits against a flat bearing-surface 331, which is formed upon the proximate side of the arm 33 of the flier, the said face 45 working in contact with the surface 331 in the 95 movements of the presser-finger. A cap-plate

6 is located at the outer side of the presser-finger and is secured in place by means of screws 7 7. The said cap-plate contacts with the outer face 46 of the presser-finger and 5 serves to keep the presser-finger in place upon the blocks. The presser-finger is guided laterally by the inner face of the said cap-plate and the opposing bearing-surface 331 on the arm 33 of the flier. The positions of the slots 10 44 44 are such as to enable the presser-finger to swing or move in a radial direction and to cause the presser-finger while moving radially to move also bodily in the direction of its length, so that the shoe of the presser shall 15 travel inward and outward in a substantially horizontal direction, as previously mentioned. In the illustrated embodiment of the invention the slots are formed and positioned so as to cause the presser-finger to swing or turn 20 about a center of motion which is located, as indicated at *x*, Fig. 1, at a point in the neighborhood of the upper end of the bobbin and also midway or approximately midway radially of the spindle and bobbin between the 25 periphery of the empty bobbin and that of a full load of roving wound upon the said bobbin. Thus the said slots constitute arcs of a circle having its center at the point *x*. The presser-finger is shown in full lines in Fig. 1, 30 with the shoe thereof occupying the innermost position of the said shoe—namely, in contact with the periphery of an empty bobbin 2, the said bobbin being shown in full lines. The said figure shows in dotted lines 35 the outline of a full load of roving wound upon the said bobbin. Preferably the slots 44 44, which are formed in the body of the presser-finger, are curved, and the opposite sides of each of the blocks or bushings 5 5 are 40 flattened to work in contact with the sides of the corresponding slot 44.

In conformity with the invention the blocks 5 5 are formed of separate pieces, which are removably applied to the arm 33 of the flier. 45 The arm 33, which is tubular to permit of the passage of the roving therethrough on its way from the boss or nose 31 of the flier to the lower portion of the presser-finger, has formed thereon projecting hollow studs or nipples 34 50 34. The blocks or bushings 5 5 are mounted upon the said hollow studs or nipples, which latter are internally screw-threaded. The stems of the screws 7 7 pass through holes 61 61, which are formed through the cap-plate 55 6, and also pass centrally through the blocks or bushings 5 5, and their inner ends enter the hollow studs or nipples. By the engagement of the threads of the said screws with the internal threads of the said hollow studs 60 or nipples the cap-plate and blocks or bushings are held properly in position. The hollow studs or nipples are formed integral with the arm 33 of the flier, they being produced

by casting the flier with enlargements upon the side of the said arm and subsequently 65 milling the said enlargements exteriorly down to the proper size and shape, boring them, and internally threading them. The said hollow studs or nipples serve a twofold purpose. In the first place they constitute supports for 70 the blocks or bushings 5 5, by which the latter are held in proper position. In the second place they afford proper support for the inner ends of the securing-screws 7 7 and enable a sufficient length of thread to be provided for engagement with the said ends of the screws. The wall of the tubular arm is too thin to permit of being properly screw-threaded. The blocks or bushings 5 5 are bored, as at 51, for the passage of the securing-screws 7 7 therethrough. They are also counterbored, as at 52, to enable them to be fitted upon the exterior of the hollow studs or nipples. The said blocks or bushings enable more bearing-surface for contact with the 85 sides of the slots 44 44 to be provided than conveniently possible in the case of screws or rivets. They are conveniently removable and renewable after wear occurs. Studs or rivets which have been employed heretofore in the 90 like position wear through the action of the presser-finger and permit the latter to become loose. The said blocks or bushings also constitute distance-pieces by means of which the cap-plate is held separated properly from the 95 side of the arm 33 to prevent the presser-finger from binding in its movements. The cap-plate 6 covers the slots 44 44 at the outer side of the presser-finger while the flier is in actual 100 operation and serves to exclude dust or lint from the said slots. It constitutes also a distance-piece by means of which the outer ends of the securing-screws 7 7 are held in the proper positions—that is to say, whereby the 105 said outer ends are kept at the proper distance apart and are prevented from becoming bent or sprung. In some embodiments of the invention the screws 7 7 may be replaced by rivets or other substitutes; but preferably I 110 employ screws, because they admit of being removed for the purpose of renewing worn parts whenever required.

I claim as my invention—

1. The combination with the flier-arm, and the slotted presser-finger, of the blocks or 115 bushings within the slots of the presser-finger, securing means passing through the said blocks or bushings and connecting the latter with the flier-arm, and means to confine the presser-finger upon the said blocks or bushings.

2. The combination with the flier-arm, and the slotted presser-finger, of the blocks or 120 bushings within the slots of the presser-finger, the cap-plate at the outer ends of the said blocks or bushings, and securing means pass-

ing through the cap-plate and blocks or bushings and securing the said parts together and to the flier-arm.

3. The combination with the flier-arm provided with the hollow studs or nipples, and the slotted presser-finger, of the blocks or bushings fitting the said studs or nipples and occupying the slots of the presser-finger, the securing means passing through the blocks or bushings and into the said studs or nipples, and means to confine the presser-finger upon the said blocks or bushings.

4. The combination with the flier-arm provided with the hollow studs or nipples, and the slotted presser-finger, of the blocks or bushings within the slots of the presser-finger and engaging with the said studs or nipples, the cap-plate at the outer ends of the said blocks or bushings, and securing means passing through the cap-plate and blocks or bushings and into the said studs or nipples.

5. The combination with the flier-arm, and the slotted presser-finger, of the blocks or bushings within the slots of the presser-finger, the screws passing through the said blocks or bushings and connecting the latter with the flier-arm, and means to confine the presser-finger upon the said blocks or bushings.

6. The combination with the flier-arm and the slotted presser-finger, of the blocks or bushings within the slots of the presser-finger, the cap-plate at the outer ends of the said blocks or bushings, and the screws passing through the cap-plate and blocks or bushings and securing the said parts together and to the flier-arm.

7. The combination with the flier-arm provided with the internally-threaded studs or nipples, and the slotted presser-finger, of the blocks or bushings engaging with the said studs or nipples and occupying the slots of

the presser-finger, the screws passing through the said blocks or bushings and into the said studs or nipples, and means to confine the presser-finger upon the said blocks or bushings.

8. The combination with the flier-arm provided with the internally-threaded studs or nipples, and the slotted presser-finger, of the blocks or bushings within the slots of the presser-finger and engaging with the said studs or nipples, the cap-plate at the outer ends of the said blocks or bushings, and the screws passing through the cap-plate and blocks or bushings into the said studs or nipples.

9. The combination with the flier-arm provided with the internally-threaded studs or nipples, and the slotted presser-finger, of the blocks or bushings occupying the slots of the presser-finger, counterbored, and fitting upon the said studs or nipples, the screws passing through the said blocks or bushings and entering the said studs or nipples, and means to confine the presser-finger upon the said blocks or bushings.

10. The combination with the flier-arm provided with the internally-threaded studs or nipples, and the slotted presser-finger, of the blocks or bushings within the slots of the presser-finger, counterbored, and fitting upon the said studs or nipples, the cap-plate at the outer ends of the said blocks or bushings, and the screws passing through the cap-plate and blocks or bushings into the said studs or nipples.

In testimony whereof I affix my signature in presence of two witnesses.

FAY H. MARTIN.
